CARBURETER.

APPLICATION FILED FEB. 10, 1914.

1,231,773.

Patented July 3, 1917.

2 SHEETS—SHEET 2.

UNITED STATES PATENT OFFICE.

HARRY A. MILLER AND FRANK M. ADAMSON, OF LOS ANGELES, CALIFORNIA, ASSIGNEES, BY MESNE ASSIGNMENTS, TO MASTER CARBURETER CORPORATION, OF DETROIT, MICHIGAN, A CORPORATION OF DELAWARE.

CARBURETER.

1,231,773.

Specification of Letters Patent.

Patented July 3, 1917.

Application filed February 10, 1914. Serial No. 817,779.

To all whom it may concern:

Be it known that we, HARRY A. MILLER and FRANK M. ADAMSON, both citizens of the United States, and residents of Los Angeles, in the county of Los Angeles and State of California, have invented a new and useful Carbureter, of which the following is a specification.

This invention relates to carbureters of a type shown in a previous application of ours filed September 12, 1912, Serial No. 719,920, issued April 28, 1914, No. 1,094,674, and the objects of the present invention are to improve and refine the construction in various ways.

One object of the present invention is to construct the air and mixture passages so that the air and mixture may pass through the carbureter with high velocity, and without any slowing up at different points to cause eddy currents, particularly in the throttle, which is located immediately above the distributor. Where the throttle is constructed as a tubular shell, the velocity of the mixture varies greatly at different points and many eddy streams are formed which interfere with the proper working. Where abrupt angles occur in passages, it causes a slowing up of the mixture with condensation and decrease of power.

Another object is to improve the construction of the air damper.

Another object is to provide an adjusting screw in the independent air passage for low speed running.

Another object is to locate the openings of the distributor a short distance away from the throttle valve to prevent any capillary action which will otherwise result with the openings located appreciably closer, and another object is to arrange the mouth of a single passage closer to the throttle to concentrate suction solely on that passage to keep the engine turning over when the throttle is closed.

A further object is to improve the construction of the distributor by forming large fuel passageways for the greater portion of their length which will not be so apt to clog up, as where small holes are employed.

Referring to the drawings:

Figure 1 is a side elevation of the carbureter.

Fig. 2 is a plan view.

Fig. 3 is a section on line x^3-x^3 , Fig. 2. 55
Fig. 4 is a section on line x^4-x^4 , Fig. 3.
Fig. 5 is a section on line x^5-x^5 , Fig. 4.
Fig. 6 is a section on line x^6-x^6 , Fig. 3.
Fig. 7 is a section on line x^7-x^7 , Fig. 3.
Fig. 8 is a section on line x^8-x^8 , Fig. 9. 60
Fig. 9 is a section on line x^9 , Fig. 3.
Fig. 10 is a section on line $x^{10}-x^{10}$, Fig. 3.
Fig. 11 is a bottom plan view of the throttle.

Fig. 12 is a plan view of the throttle. 65

1 designates a float chamber with removable top 2 retained by a split ring 3, and containing float 4, which acts against levers 5 to vary the position of a vertical needle valve 6, the latter being slidably supported in the top 2, and freely passing through the float, and controlling a fuel passage formed in a double nipple 7, which is screwed in the lower wall of the float chamber, and has transverse passages 8, which communicate with the liquid fuel supply in the removable base 9, the upper rim of the latter fitting against a beveled edge 10 on the bottom of the float chamber and being held in place by a hollow nut 11. 12 is a supply pipe and 13 is a screen through which the liquid fuel must pass before it reaches the needle valve 6. By removing the single nut 11, the base 9 may be immediately removed, giving access to the interior and to the needle valve for 85 cleaning. Arranged horizontally at one side of the float chamber 1 is a cylindrical screen 14, (see Figs. 3 and 5), which is supported by a nipple 15, which has a hexagonal head 16 accessible from the outside, and by unscrewing the same, the nipple with its screen 14 may be instantly removed for cleaning. 90

The liquid fuel passes from the nipple 15 through a passage 17 into a distributor 18, 95 which consists of a solid block with a series of vertical fuel passages 19 having relatively large diameters throughout the greater portion of their length, and at the extreme upper end being contracted to relatively small orifices 20. This construction gives large passages which are not readily clogged, and the construction is easily produced as a large drill is used for the greater portion of the passage. As shown in Fig. 4, the extreme right hand passage 19 is raised some what as at 21, and its surface is very close to the surface of the throttle 22, while there

is about $\frac{1}{2}$ of an inch between the mouths of the other perforations 20, and the face of the throttle valve, to prevent the capillary action drawing liquid fuel up through the 5 orifices when the throttle is closed.

The distributor is arranged in substantially the center of the air passage as shown in Fig. 3, so that the air is divided into two streams, which pass upward on opposite sides of the distributor, and come together at the top of the distributor after forming a partial vacuum immediately above the perforations in the distributor. At one side of the distributor is a damper 23 mounted 10 on a shaft 24 provided with a controlling lever 25, which may be operated by means of a wire 26, extending through a Bowden tube 27 to any desired point.

The air passage is divided by a vertical 20 partition 28 to form a large passage 29 and a small passage 30, which latter is for low speed running. Communicating with the passage 30 is a swiveled elbow 31 which may conduct air from some heating source not 25 shown, and the air in passage 30 passes upward on each side of the distributor and over the single right hand perforation 21. To confine the air to this particular perforation when the throttle is closed, the 30 throttle 2 is formed with a narrow transverse slot 32, so that when the throttle is turned to bring this slotted portion 32 over the perforation 21, the remainder of the throttle shuts off the other perforations 19, 35 thereby confining the action of the air at this time exclusively to the single right hand perforation with the result that with the small amount of air employed, a relatively small quantity of liquid fuel is drawn to the 40 distributor, and is delivered to the engine, for the purpose of turning the engine over when the throttle is shut off.

The opening through the throttle is formed with a curved edge 33, which merges 45 with the opening 32, and requires a considerable turning movement of the throttle to expose the second perforation, and a less turning movement to expose the third perforation, while the fourth and succeeding 50 perforations of the throttle are quickly uncovered by relatively small angular movements of the throttle. This enables a very close control.

A screw 34 is arranged with its end projecting into the small air passage 30 at a point near the discharge mouth of the right hand passage 19 to regulate the amount of air passing therethrough, and this screw 55 may be adjusted to give the desired low speed, within its limits, when the throttle is shut off.

It will be noted that the walls of the opening through the throttle are substantially parallel with each other, and with easy curves. 60 This prevents eddy currents and does not re-

tard the velocity of the air. Another advantage of the solid throttle over a barrel or shell throttle is that with a shell throttle the suction causes it to fit tight against the walls in which it turns, making it hard to operate. Whereas, with the solid throttle this is prevented, and in the present construction, it is constructed a few thousandths of an inch loose, and is carried entirely by a steel shaft 35 mounted in brass bearings 36 70 formed in the walls of the carburetor. This gives a smooth movement of the throttle under all conditions, and prevents scraping or scoring of the walls. The damper 23 has a long swing, thereby presenting the least 75 abrupt angle to the passage of the air and avoiding retardation thereof. This damper may be adjusted toward or from the distributor to control the desired amount of auxiliary air, normal air being admitted in 80 a fixed amount at the right hand side of the distributor.

The distributor 19 is constructed of a single block as before described, with a projecting lug 37 in the lower right hand corner thereof, and is retained in position by a single screw 38, (see Fig. 9), the screw 38 also being shown in dotted lines, Fig. 2. By removal of screw 38, the distributor may be 90 instantly withdrawn from the carburetor 95 without dismantling any other portions.

What we claim is:

1. In a carburetor, a chamber, a distributor in said chamber provided with a series of liquid fuel passages opening at the upper edge thereof, a cylindrical throttle valve arranged with its face slightly above the upper edge of the said distributor, means for conducting air into said chamber, a partition in said chamber dividing the chamber 100 into a narrow passage and wide passage, the narrow passage concentrating the passage of air over the mouth of the single liquid fuel passage, the wider air passage 105 acting to direct the air over the mouths of the other liquid fuel passages, the throttle having a transverse recess communicating with its main recess adapted to register with the said single fuel passage to coöperate with the said narrow air passage and concentrate the suction on the associated single fuel passage.

2. In a carburetor, a chamber, a distributor in said chamber provided with a series of liquid fuel passages opening at the upper edge 110 thereof, a cylindrical throttle valve arranged with its face slightly above the upper edge of the said distributor, means for conducting air into said chamber, a partition in said chamber dividing the chamber into a narrow 115 passage and wide passage, the narrow passage concentrating the passage of air over the mouth of the single liquid fuel passage, the wider air passage acting to direct the air over the mouths of the other liquid fuel 120 passage.

- passages, the throttle having a transverse recess communicating with its main recess adapted to register with the said single liquid fuel passage to coöperate with the said 5 narrow air passage and concentrate the suction on the associated single fuel passage, the said distributor having a raised portion on its upper edge through which the said single air passage extends, the said raised 10 portion lying close to the surface of the throttle.
3. In a carbureter, in combination with a chamber, a distributor in said chamber, a throttle above the distributor, there being 15 air passages on each side of the distributor, a damper in one of said air passages, and its upper edge movable toward and from the distributor to vary the amount of air passing on that side of the distributor, the 20 damper being of appreciable length and pivoted at its lower end to avoid a sharp angle in the air passage.
4. In a carbureter, an air chamber, a distributor in said air chamber, a throttle above 25 said distributor, a partition in said air chamber dividing it into a narrow air passage and a wide air passage, the distributor having a series of liquid fuel passages, the narrow air passage acting to confine the air passing therethrough to a single liquid fuel passage, and the other of which directs air over the 30 mouths of the other fuel passages, and means to control the passage of air through both 65 of air therethrough.
5. In a carbureter, a chamber, a distributor 35 in said chamber provided with a series of liquid fuel passages opening at the upper edge thereof, means for conducting air into
- said chamber, and a partition mounted in and dividing said chamber into a narrow 40 passage and a wide passage, said narrow passage concentrating the passage of air over the mouth of a single liquid fuel passage, the wider air passage acting to direct air over the mouths of the other liquid fuel 45 passages.
6. In a carbureter, an air chamber, a distributor in said air chamber, a throttle above 50 said distributor, a partition in said air chamber dividing it into a narrow passage and a wide passage, the distributor having a series of liquid fuel passages, the narrow 55 passage acting to confine the air passing therethrough to a single liquid fuel passage, and means to regulate the passage of air through the narrow passage.
7. In a carbureter, an air chamber, a distributor in said air chamber having a series 60 of liquid fuel passages therein, a throttle above said distributor, a partition in said air chamber dividing it into separate passages, one of which confines the air passing therethrough to a single liquid fuel passage and the other of which directs air over the mouths of the other fuel passages, and means to control the passage of air through both 65 of air therethrough.

In testimony whereof, we have hereunto set our hands at Los Angeles, California this 20 day of January, 1914.
